SAFETY CLOTHESLINE CLAMP

Andrew Yagich, Cleveland, Ohio

Application October 12, 1938, Serial No. 234,717

1 Claim. (Cl. 24—81)

The present invention relates to new and useful improvements in safety clothesline clamps and has for its primary object to provide, in a manner as hereinafter set forth, novel means whereby a clothesline may be firmly secured at one or more intermediate points to a suitable support in a manner to prevent the entire line from falling in the event it should break.

Other objects of the invention are to provide a safety clothesline clamp of the aforementioned character which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of an embodiment of the invention, showing two of the clamps in use on a clothesline.

Figure 2 is a vertical sectional view, taken substantially on the line 2—2 of Fig. 1.

Figure 3 is a top plan view of the invention with the clothesline removed.

Figure 4 is a view in side elevation of a slightly modified form of the invention, showing the device mounted on a wall.

Figure 5 is a cross sectional view, taken substantially on the line 5—5 of Fig. 4.

Figure 6 is a detail view in perspective of the slidable jaw.

Referring now to the drawings in detail, it will be seen that the reference numeral 1 designates a substantially U-shaped body or member of any suitable metal which is adapted to be mounted on the upper end portion of a post or pole 2. The upstanding end portion 3 of the member 1 is formed to provide a stationary jaw 4.

Projecting laterally from the end portion 3 of the member 1 is a pair of integral, apertured ears 5. The reference numeral 6 designates a clamp in the form of a metallic strap which is secured by bolts 7 to the ears 5 and which is engageable around the post or pole 2 for firmly securing the member 1 in position thereon. This is illustrated to advantage in Fig. 3 of the drawings.

Projecting inwardly from the end portion 8 of the member 1 is an integral guide 9. The reference numeral 10 designates a slidable jaw which is

mounted in the member 1 beneath the guide 9 for coaction with the stationary jaw 4.

Threadedly mounted in the end portion 8 of the member 1 is a thumb screw 11. The slidable jaw 10 is rotatably mounted on the inner end portion of the thumb screw 11 for actuation thereby toward and away from the stationary jaw 4. The inner end portion of the thumb screw 11 has formed therein a peripheral groove 12 which receives a transverse pin 17 in the jaw 10 for rotatably securing said jaw to said screw. The reference numeral 13 designates a clothesline between the jaws 4 and 10.

It is thought that the manner in which the device functions will be readily apparent from a consideration of the foregoing. The member 1 is mounted on a pole or post 2 and the clothesline 13 is inserted therein at an intermediate point. The slidable jaw 10 is then moved toward the stationary jaw 4 through the medium of the thumb screw 11 in a manner to firmly clamp the clothesline therebetween. Any suitable number of the clamps may be attached to the line at spaced intermediate points. In Fig. 1 of the drawings, two of the devices have been shown in use. It will be observed that the construction and arrangement is such that the clothesline may be engaged in the clamp at any intermediate point. If desired, the clamp 6 and the bolts 7 may be omitted and screws inserted through the apertured ears 5 for mounting the device on a wall. It will be noted that the upper portion of the slidable jaw 10 is recessed, as at 14, to accommodate the guide 9.

In the arrangement shown in Fig. 4 of the drawings, the elements 5, 6 and 7 are omitted and a screw 15 is substituted therefor on the end portion 3 of the member 1 for mounting the device on a wall, as at 16. In other respects the embodiment shown in Fig. 4 is similar in construction and operation to that illustrated in Figs. 2 and 3 of the drawings.

It is believed that the many advantages of a safety clothesline clamp constructed in accordance with the present invention will be readily understood and although preferred embodiments of the device are as illustrated and described, it is to be understood that further modifications and changes in the details of construction may be resorted to which will fall within the scope of the invention as claimed.

What is claimed is:

A safety clamp of the character described comprising a substantially U-shaped metallic member for the reception of a clothesline, means on

one end of the member for mounting same horizontally on a support, an integral stationary jaw in said one end of the member, an integral guide projecting inwardly from the other end portion of the member, a slidable jaw mounted in the member and operable beneath the guide, said slid-
5 able jaw having its upper portion recessed for the

reception of the guide, and a thumb screw thread-
edly mounted in said other end portion of the
member and operatively connected to the slidable
jaw for moving same toward the stationary jaw
for clamping the clothesline therebetween.

ANDREW YAGICH.
